UNITED STATES PATENT OFFICE.

CHARLES W. RODECKER, OF CHARLESTON, WEST VIRGINIA, ASSIGNOR OF ONE-THIRD TO JACK P. McNEILL AND ONE-THIRD TO JAMES W. HOLLADAY, BOTH OF CHARLESTON, WEST VIRGINIA.

WINDOW-SCREEN.

1,146,818.

Specification of Letters Patent. Patented July 20, 1915.

Application filed February 6, 1914, Serial No. 817,016. Renewed June 9, 1915. Serial No. 33,198.

To all whom it may concern:

Be it known that I, CHARLES W. RODECKER, a citizen of the United States, residing at Charleston, in the county of Kanawha and 5 State of West Virginia, have invented a new and useful Window-Screen, of which the following is a specification.

This invention relates to window screens of that type in which the screen fabric is 10 adapted to be wound upon a spring roller and one of the objects of the invention is to provide a screen of this type having its roller adjustable longitudinally so as to be used in connection with a screen fabric of 15 any desired width.

A further object is to provide an extensible housing for use in connection with the roller, said housing being adapted to be secured within the window frame or casing 20 and being adjustable so as to fit tightly against the sides thereof, the extension or shortening of the casing resulting in a corresponding adjustment of the roller contained within the casing.

25 A further object is to provide a roller which will extend automatically when the casing is elongated and thus remain constantly in engagement with the end walls of the casing.

30 Another object is to provide a screen the casing of which can be readily placed in position within a window frame or casing and which can be easily removed whenever desired.

35 A further object is to provide a screen the fabric of which has means whereby it can be detachably connected to a window sash so that, when the sash is moved out of its normal position, the screen fabric will be 40 unwound from its roller.

With the foregoing and other objects in view which will appear as the description proceeds, the invention resides in the combination and arrangement of parts and in 45 the details of construction hereinafter described and claimed, it being understood that changes in the precise embodiment of the invention herein disclosed, can be made within the scope of what is claimed, without departing from the spirit of the invention.

In the accompanying drawings, the preferred form of the invention has been shown.

In said drawings:—Figure 1 is a front elevation of a window having screens, such 55 as constitute the present invention, com-

bined therewith. Fig. 2 is a central vertical section of the parts shown in Fig. 1. Fig. 3 is a central longitudinal section through the housing of one of the screens, the roller being shown therein partly in 60 section and partly in elevation. Fig. 4 is a vertical transverse section through the screen and its housing. Fig. 5 is a perspective view of the housing. Fig. 6 is a perspective view of the roller. Fig. 7 is a perspective view of a portion of a guide strip adapted to be used in connection with the screen.

Referring to the figures by characters of reference 1 designates a window frame or 70 casing having upper and lower sashes 2 and 3 slidably mounted therein as ordinarily. Any suitable means, shown generally at 4, may be provided for locking either of the sashes against movement in one direction. 75 This means constitutes no part of the present invention but has been disclosed in a co-pending application filed by me.

A screen is adapted to be used in connection with each sash, the two screens being 80 duplicates. Each of these screens includes a casing such as shown in detail in Fig. 5. This casing is made up of an elongated box-like member 5 one end of which is open while its other end is closed, as indicated 85 at 6, there being inwardly directed guide flanges 7 formed along the longitudinal edges of the section 5. Another elongated box-like section 8 is slidably mounted with in the section 5 and is retained therein by 90 the flanges 7 which lap the longitudinal edges of the section 8, the outer end of said section being closed, as indicated at 9 while its inner end is open. The two sections thus co-operate to form a longitudinally adjustable casing. The section 8 has a longitudinal slot 10 in one wall thereof and into 100 which extends a clamping screw 11, the head 12 of the screw bearing upon the inner face of said wall while the threaded portion of the screw, which projects through and beyond the adjacent wall of the section 5, carries a clamping nut 13 or the like. Thus it will be seen that by tightening the nut upon the screw the two sections can be 105 clamped together after being adjusted to any desired positions relative to each other. Slot 10 is preferably so located that it will at no time be exposed outside of the casing during the adjustment of said casing. 110

The end wall 6 of the casing has a slot 14 adapted to receive the angular trunnion 15 of a roller 16, said trunnion projecting into the roller and forming part of a stem 17. A coiled spring 18 is secured at one end to the stem and at its other end to the roller so that, when the said roller is rotated, in one direction, the spring 18 will be wound tightly about the stem and, when roller 16 is released, the spring will operate to return it to its initial position. The other end wall 9 of the casing has an opening 19 to receive a cylindrical trunnion 20 extending from a tubular extension 21 carried by the roller 16. This extension telescopes into one end of the roller and a spring 22 is housed within the roller and extension and serves to press said extension normally outwardly. A slot 23 is formed longitudinally within extension 21 and a lug 24 is struck inwardly from the roller 16 so as to project into the slot and thus limit the outward movement of the extension.

The screen fabric, such as shown at 25, is cut to a width equal to the width of the window opening and is secured at one end to the roller 16 and its extension. This fabric is normally wound upon the roller and the free end of the fabric has a reinforcing strip 26 preferably of metal secured thereto and provided, at its center, with an attaching element, such as a ring or loop 27.

When it is desired to attach the screen to the lower sash 3, the nut 13 is loosened and the housing or casing, with roller 16 therein, is placed on the sill of the window and then elongated so as to bring the end walls 6 and 9 firmly in engagement with the sides of the window casing. During this extension of the housing, the roller 16 will be automatically extended by spring 22 so as to maintain its trunnions 15 and 20 within the openings 14 and 19 respectively. After the casing has been thus positioned, the nut 13 is tightened so as to clamp the two sections 5 and 8 together. The free end of the screen fabric 25 is then attached to the lower rail of sash 3 by placing the loop or ring 27 in engagement with a hook or button 28 extending from the middle of the lower rail. It will be apparent therefore that when the sash 3 is raised, the screen fabric will be unwound from the roller 16, this operation causing the spring 18 to gradually wind within the roller. The screen fabric will thus be held taut at all times. When the sash is lowered, the spring 18 causes the roller 16 to rotate and automatically take up the slack in the screen fabric.

The same kind of a screen is to be used in connection with the upper sash 2 but, in applying the screen to the upper sash the same is secured between the upper portions of the window frame or casing and the screen fabric is attached to the middle portion of the upper rail of the upper sash. In addition, guide strips, such as shown in Fig. 7, may be secured along the parting strips. Each of these guide strips is preferably formed of light sheet metal and includes an attaching or base strip 29 and an outstanding guide strip 30, said guide strip or flange lying close to the path of the sash 2, thus forming a channel in which the edge portion of the screen fabric is adapted to work. An arm 31 may be extended inwardly from the upper end of each guide strip so as to constitute a supporting bracket on which the upper casing may be mounted, as indicated in Fig. 2. The side edges of the screen connected to the lower sash are preferably guided by bead or guide strips 32 secured along the sides of the window frame or casing close to the path of the sash.

As shown particularly in Fig. 2, a flexible guard strip 33 may be attached to the bottom of the lower rail of the upper sash 2 so as to contact with the outer face of the lower sash 3 and thus prevent flies from passing between the lower sash and the lower rail of the upper sash.

What is claimed is:—

A window screen including telescopically connected casing sections each having its outer end closed and provided with one open face, the ends of the sections being pressed inwardly and provided with trunnion receiving openings, a roller having trunnions extending therefrom and into the openings, said roller being made up of sections, a spring for controlling the rotation of the roller, a spring housed within the roller and between the sections for holding the trunnions seated within the openings at all times during the extension and contraction of the casing, said inwardly pressed portions constituting thrust bearings for the roller, and means for securing the casing sections together to prevent automatic extension of the roller and casing.

In testimony that I claim the foregoing as my own, I have hereto affixed my signature in the presence of two witnesses.

CHARLES W. RODECKER.
